PEDESTAL TYPE BASE
William B. French, R.R. 2, Fairmount, Ind.
Filed May 4, 1961, Ser. No. 107,863
1 Claim. (Cl. 248—158)

The invention relates in general to mounting bases and in particular to legged pedestal mounting bases.

An object of this invention is to provide a base for mounting fixtures and that is comprised of a minimum of parts that can be easily assembled or disassembled by unskilled and untrained persons.

An object of this invention is to have the total cubic measurement of the combined disassembled parts be of a minimum for storing or shipping.

An object of this invention is to provide an attractive pedestal base on which may be supported such items as chair seats, table tops, display racks, and other fixtures in general that are appropriate to this type of support.

Other objects and a better understanding of the invention may be had when reference is made to the description and the drawing in which:

FIG. 1 is a perspective view of a preferred embodiment of my invention in fully assembled condition;

FIG. 2 is a fragmentary, exploded perspective illustrating the mode of cooperation among the two, identical leg members and the U-bolt which constitute elements of that embodiment; and

FIG. 3 is a side elevation of the structure shown in FIG. 1, parts being shown in section for clarity of illustration.

According to the present invention, I provide a pair of identical, arched leg members 2 and 3 which may be advantageously stamped from sheet or plate metal. As is most clearly to be seen in FIGS. 2 and 3, each leg member is formed to define a peak near the center point of its length, and the member 2 is formed with a notch opening through its lower edge while the member 3 is formed with a similar notch opening through its upper edge, substantially at that peak. Each notch has a width which is substantially equal to the thickness of the leg member, and has a vertical depth substantially equal to one-half the vertical width of the leg member. Thus, when the two leg members 2 and 3 are brought together with their notches in interfitting relation, each notch snugly receives a portion of the cooperating leg member, the upper and lower edges of the peak regions of the two leg members are disposed, respectively, in substantially flush relation, and the foot means 7 provided at each end of each leg member will be disposed substantially in a common plane. Additionally, the two leg members 2 and 3 will be disposed substantially perpendicular to each other to define four crotches, each in the shape of a right angle, with their apices directed inwardly and spaced 90° from each other.

A tubular upright 1 is formed at its lower end with four slots, each opening through the lower end of the upright. Said slots are disposed at 90° intervals around the periphery of the upright and are of equal vertical heights. It will be apparent that, after the leg members 2 and 3 have been assembled in the manner above described, the upright 4 can be cooperatively associated therewith, with each slot snugly receiving a portion of a leg member 2 or 3. The peripheral width of each slot

2

is substantially equal to the thickness of the leg members 2 and 3, and portions of each leg member equally and oppositely spaced from the center of length of said leg member are snugly received, respectively, in diametrically-opposite ones of said slots, whereby the upright acts to secure the leg members against relative movement about the vertical axis at their point of interengagement.

A U-bolt 4 may be arranged with its bight underlying the leg members 2 and 3 in the region of interengagement of said leg members, the opposite arms of the U-bolt being arranged to pass through diametrically-opposite crotches defined between the leg members as is clearly illustrated in FIGS. 2 and 3. The arms of the U-bolt 4 extend thence upwardly within the upright 1, the U-bolt 15 being so proportioned and designed that the distal ends of its arms will extend somewhat above the upper end of the upright 1 when the bight of the U-bolt is engaged against the lower edges of the leg members 2 and 3.

A bearing plate 5 of any suitable construction is arranged to be supported at the upper end of the upright 1. The distal ends of the arms of the U-bolt 4 penetrate said plate 5; and nuts 6 may be threadedly engaged with the projecting upper ends of the U-bolt arms to bear against the plate 5 so that, as said nuts are turned home, 20 the bight of the bolt 4 will be drawn firmly into retaining engagement with the lower edges of the leg members 2 and 3.

The foot means 7 may preferably be of the well known self-leveling type.

It will be obvious that any desired device such as a chair seat, a table top, a display rack or other supported element may be mounted upon the bearing plate 5 and will thus be supported upon the pedestal or base of the present invention.

Although the invention has been described in its preferred form with a certain degree of particularity, it is understood that the present disclosure of the preferred form has been made only by way of example and that various details of the members composing the assembly 35 may be changed without departing from the spirit and the scope of the invention as hereinafter claimed.

What is claimed is:

A pedestal type base comprising two identical, arched leg members, each provided with foot means at each end thereof, each leg member being provided, centrally of its length, with a notch proportioned and designed snugly to receive the thickness of the other leg member, the notch of one leg member opening through the upper edge thereof and the notch of the other leg member opening through the lower edge thereof and each notch having a vertical depth substantially equal to one-half the vertical width of its leg member whereby, when said notches are interfitted, said leg members will be assembled in perpendicular relation to each other with their four foot means disposed substantially in a common plane, a tubular upright formed at its lower end with four slots of substantially equal vertical heights opening through said lower end of said upright and spaced 90° from each other, each such slot having a transverse width substantially equal to the thickness of a leg member and portions of each leg member equally and oppositely spaced from the center of length of said leg member being snugly received, respectively, in diametrically-opposite ones of 45 said slots, a U-bolt having its bight engaged beneath said 50 55 60 65

leg members in the region of their interengagement, with the opposite arms of said U-bolt disposed within said tubular upright and passing respectively through diametrically-opposite crotches between said leg members, a bearing member supported at the upper end of said tubular upright, said U-bolt arms penetrating said bearing member, and means engaging the distal ends of said arms and cooperating with said bearing member to urge the bight of said U-bolt into cooperating engagement with said leg members.
